CLAIM

I claim the ornamental design for a perforated spoon, as shown and described.

DESCRIPTION

FIG. 1 is a right side view of a perforated spoon.
 FIG. 2 is a left side view of the claimed design.
 FIG. 3 is a front view of the claimed design.
 FIG. 4 is a rear view of the claimed design.
 FIG. 5 is a top view of the claimed design.
 FIG. 6 is a bottom view of the claimed design; and,
 FIG. 7 is a perspective view of the claimed design.
